(57)

CLAIM

The ornamental design for a LED luminaire having a mounting system, as shown and described.

DESCRIPTION

FIG. 1 is a front elevational view of the LED luminaire having a mounting system, of the present invention; FIG. 2 is a back elevational view thereof; FIG. 3 is a top, back, left perspective view thereof; FIG. 4 is a top, back, right perspective view thereof; FIG. 5 is a left elevational view thereof; FIG. 6 is a right elevational view thereof; FIG. 7 is a top plan view thereof; and, FIG. 8 is a bottom plan view thereof, wherein the elements that are shown in broken lines are disclaimed.
